Application February 8, 1940, Serial No. 317,924
In Great Britain March 23, 1939

16 Claims. (Cl. 242—35.5)

This invention relates to cheese-winding apparatus in which a completed package is automatically swung out of winding position and replaced by an empty package support to which the thread is transferred.

The apparatus according to the invention is particularly suitable for the winding of threads of artificial filaments continuously with their production, since not only does it provide for the continuous winding of the thread during the substitution of an empty support for a completed package, but reduces any tendency to snatching of the thread, such as might interfere with the continuity of production of the thread.

According to the invention, a pair of winding spindles protrude from opposite sides of a trunnion, the spindle axes lying on opposite sides of the trunnion axis, and means are provided to position one of the spindles alongside a traverse guide by which thread is led to a package support on that spindle, the other spindle meanwhile lying in a position from which the completed package can be removed and replaced by an empty support. When a package is completed, the trunnion is caused to rotate, the offset position of the winding spindle with respect to the trunnion axis ensuring that the thread still proceeding from the traverse guide to the package does not fall over the end of the package, but remains in contact with its surface, so that winding still proceeds until the thread engages a fixed thread guide, which controls the feeding of the thread to the package during the remainder of the rotation.

The traverse guide is arranged to move outwards as the diameter of the cheese increases and it is convenient to return the guide to its innermost position soon after the trunnion begins to be moved, this return of the guide facilitating the engagement of the thread with the fixed guide by which the path of the thread is controlled during the remainder of the trunnion movement. Suitable guides are provided on the trunnion to lead the thread into proximity to the empty support as the latter approaches winding position and suitable means, such as notches on the carrier for the package support, are provided to engage the thread to the empty support while breaking it from the completed package, the traverse guide remaining threaded.

The spindles are preferably driven by gearing that continuously reduces the angular speed of the spindles and thereby maintains the peripheral speed of the package constant. This gearing begins to operate as soon as winding begins

on the empty support, and is re-set when winding is completed on the support and the support is brought to rest. At the time of transferring the thread to the empty support, both full and empty supports are driven at the same peripheral speed to enable the transfer to take place smoothly.

The thread remaining in the traverse guide, the substitution of an empty support for a completed package and the transfer of the thread to the empty support are effected simply by the rotation of the trunnion carrying the winding spindles. Except, therefore, that the spindles rotate and the traverse guide continues its motion, the operation is completed without the use of moving parts to control the thread.

Picking up of the yarn by the notches on the carrier for the empty support throws tension on the yarn between the notches and the completed package, so that the yarn breaks in this length, and the yarn proceeding to the empty support is permitted to be taken up smoothly by the support. In this way snatching of the yarn such as might cause a break between the winding device and the jet is avoided.

The invention will now be described in greater detail with reference to the accompanying drawings, in which:

Fig. 1 is a diagrammatic front elevation of the winding mechanism applied to a dry-spinning apparatus for the production of threads of artificial filaments;

Fig. 2 is a diagrammatic side elevation taken on the line 2—2 of Fig. 1;

Fig. 3 is a detail of Fig. 2 to a larger scale;

Fig. 5 is a detail of the drive to the gear-box shown in Fig. 4;

Fig. 6 is a front elevation to a larger scale of the winding mechanism shown in Fig. 1;

Fig. 7 is a front elevation of the main driving shaft for the winding mechanism and dry-spinning apparatus;

Fig. 8 is a part-sectional side-elevation taken on the line 8—8 of Fig. 6;

Fig. 9 is a plan view of the left-hand side of Fig. 8;

Figs. 10 and 11 illustrate the transfer of thread from a completed package to an empty support;

Fig. 12 shows the means for bringing a completed package out of winding position;

Fig. 13 shows in part-section the driving connections to the winding spindles;

Fig. 14 is a section along a winding spindle;

Fig. 15 shows a detail of Fig. 2 to a larger scale; Fig. 16 is a detail of Fig. 6 to a larger scale; and Figs. 17 and 18 are side elevation and cross-section respectively of a ribbon-breaking mechanism.

A trunnion casing 1 (Figs. 1 and 6) of substantially rectangular cross-section with rounded corners is mounted in frames 2 to turn about a horizontal axis A—A and from a pair of opposite sides of the casing package-carrying spindles 3 protrude, the spindles being parallel to each other and lying respectively above and below the trunnion axis (see Figs. 2, 9, 10 and 11). The spindles 3 comprise shafts 4 bearing helical gears 5 meshing with gears 6 on horizontal shafts 7 running lengthwise of the casing 1 (Figs. 8 and 13). Alternatively the spindles 3 may be connected to the shafts 7 by bevel gears 8, as shown in Fig. 9 and Fig. 14.

The casing 1 extends along any desired number of spinning cells, provision for three cells C, each producing two threads, being shown in Figs. 1 and 6, and provides a pair of spindles 3 for each thread produced in the cells. With the thread 9 delivered downwardly to one side of the casing 1, the carrier-spindle 3 bearing the support 10 for that thread lies below the level X—X of the trunnion axis (Fig. 11) and the casing is arranged to rotate clockwise so as to carry that spindle downwardly, i. e. further below the level X—X towards a doffing position, at the same time bringing the other spindle containing an empty support 10 upwardly and over the trunnion axis into winding position.

Alongside the winding position is mounted a traverse mechanism (Fig. 8) comprising a guide 12 having a stroke appropriate to the length of cheese to be wound, the guide, moreover, being capable of movement away from the spindle as the cheese increases in size, as will be described later. Extending from the casing 1 is a fixed guide 13 with its inner end 14 spaced from the winding spindle by an amount slightly in excess of the full radius of the cheese, the guide then inclining upwardly from this point, so that as the spindle is carried downwardly by rotation of the trunnion, the guide is approximately horizontal when the rotation has carried its inner end 14 slightly below the line of operation of the traverse guide 12 (see Fig. 10).

One side of the fixed guide carries hooks 15, 16 facing each other (Fig. 9); the thread 9 being carried between the hooks when the casing rotates and when the traverse guide 12 is moved near the commencement of the trunnion movement, as will be described later. In the interval before the thread becomes engaged by the fixed guide, the offset position of the winding spindle 3 with respect to the axis of the casing 1 ensures that the field of traverse of the thread remains within the length of the package. Thereafter, notwithstanding the continued traversing of the guide, the fixed guide 13 continues to direct the thread to the package and prevents any likelihood of the thread falling over the inner end 17 of the package (Fig. 10), the hook 15 at the inner end of the guide 13 extending sufficiently from the casing to prevent the thread from reaching the inner end of the cheese during the rotation of the trunnion. The last turns of yarn build up as a slight ridge near the inner end of the cheese, which facilitates finding the yarn end in subsequent use of the cheese.

As the casing continues its rotation the thread 9 passes round one corner 18 of the casing and

then round the next, 19, being engaged by guide rods 20 secured near these corners (Fig 11). As the spindle with the empty support reaches winding position, the thread, which continues to be engaged by the still moving traverse guide 12, engages a circular shoulder 21 on the carrier support. This shoulder is notched (see 22), and the thread entering one of the notches is carried against a fixed pin 23 near the shoulder and is increasingly tensioned until it breaks near the inner end of the fixed guide 13 associated with the completed package. At the same time winding commences on the empty support 10 and the tail of thread extending from the traverse guide 12 to the point where it was broken is also wound on to the end of the support to serve as a tail that may be tied to the head of another package in a creel.

As shown in Fig. 8, the traverse guide 12 is carried by a rod 24 having a follower 25 engaging a traverse cam 26 mounted on a shaft 27 and driven by bevel gears 28 from a shaft 29 serving all the traverse mechanisms. A clutch 30, operated by a lever 31, a link 32, and an eccentric 33 from a hand-lever 34 enables any individual traverse guide 12 to be brought to rest.

The traverse rod 24 is carried in a frame 35 pivoted on a bearing 36 co-axial with the shaft 27, so that the guide 12 may be moved towards and away from the axis of its package spindle 3 without interfering with the driving of the guide 12 by the cam 26. A downward extension 37 of the frame 35 acts as a weight to cause the guide 12 to press against the surface of the package during winding. Adjustable weights 38 enable the pressure of the guide to be varied. The extension 37 carries a lug 39 by which the frame 35 is swung (simultaneously with the frames at the other spindles) under the control of a slide rod 40 during the doffing and donning period, so as to re-position the guide 12 for the winding of a new package. The operating means for the slide rod 40 are described later.

At one end of the trunnion 1 is secured a worm-wheel 41 meshing with a worm 42 (Fig. 12) to enable the trunnion to be turned by operation of a hand-wheel 43 fixed to the worm shaft 44. A spring plunger 45 normally holds the trunnion locked with one set of spindles 3 in winding position, and has to be released manually to permit the trunnion to be turned. When a half-turn has been made, the plunger snaps back into locking position.

Rotation of the trunnion does not interrupt the drive to the spindles 3. As shown in Fig. 13, the spindle-driving shafts protrude from the trunnion casing into a casing 46 rotatable with the trunnion, and co-axial with it. A central shaft 47 extends from the casing 46 to carry a sprocket 48 and is geared to one shaft 7 by pinions 49. A sleeve 50 surrounding the shaft 47 extends from the casing 46 to carry a sprocket 51 and is geared to the other shaft 7 by pinions 52.

The sprockets 48, 51 are chain-driven from infinitely variable gear-boxes 53, 54 (Figs. 2, 3 and 6), the output shafts 55, 56 of which are provided with sprockets 57, 58. The input shafts 59, 60 of the gear-boxes are provided with sprockets 61, 62 chain-driven from sprockets 63, 64 on a clutch shaft 65 to a sprocket 66 on which the main drive is supplied from any suitable source of power (not shown).

Two clutches 67, 68 on the shaft 55 (Fig. 7) are operated independently of each other by forks 69 on shafts 70 by means of hand-levers 71

(Figs. 2 and 6). The clutches enable one or other of the gear boxes 53, 54 to be in operation to drive the one set of spindles 3 at which winding is taking place. Both gear-boxes are in operation simultaneously in the transfer period, as is explained later.

The rate at which the clutch shaft 65 is driven determine the rate at which thread is delivered from the spinning machine, a sprocket 72 (Figs. 1 and 6) on the shaft 65 driving a sprocket 73 on a shaft 74 carrying a waste-roller 75 that rotates with a peripheral speed equal to the rate at which the thread 9 is to be wound at the spindles 3. The shaft 74 carries a sprocket 76 driving a sprocket 77 on a shaft 78 that serves to drive the pumps of the spinning machine and the control for the infinitely variable gear-boxes 53, 54.

The pumps 79 are driven by a shaft 80 having a sprocket 81 driven from a sprocket 82 on a shaft 83 parallel to the shaft 78. Interchangeable gears 84, 85 on the shafts 78, 83 are connected by an idler gear 86 on a banjo-plate 87 (Fig. 15) to enable the pump-shaft 80 to be driven at any desired rate from the waste-roller shaft 74.

The shaft 88 carries a cam 89 by which a ratchet-wheel 90 is driven, through a lever 91, link 91, lever 92, and pawl 93 (Fig. 5). On the shaft 94 of the wheel 90 is an eccentric portion 95 on which a pawl 96 is carried to drive a ratchet wheel 97 slowly about a shaft 98. On stub axles 99 carried by the wheel 97 are carried pinions 100, 101 meshing with pinions 102, 103 (Fig. 4), the one pinion 102 being secured to the shaft 98 and the other pinion 103 being held to the gear-box 104. The ratios of the pairs of pinions 100, 102 and 101, 103 differ slightly, with the result that the drive from the wheel 97 to the shaft 98 through the epicyclic train formed by the pinions effects a considerable speed reduction, the timing being adjusted so that a cam 105 carried by the shaft 98 makes one half-revolution in the time required to complete a package.

The cam 105 has the profile shown in Fig. 3. One half 106 of the cam is semicircular; the other half 107 has a steady lift ending in a sudden drop 108. Two follower levers 109, 110 are mounted on pivots 111 so as to be engaged by diametrically opposite points of the cam 105. Chains 112, guided by sprockets 113, connect the levers 109, 110 to wedges 114 mounted in slides 115 alongside the gear boxes 53, 54 (Figs. 3 and 6). The wedges have slots 116 to embrace the control spindles 117 of the gear-boxes and thus permit the wedges to lie between a head 118 on each spindle 117 and a head 119 on a control sleeve 120 surrounding the spindle 117. The wedging action resulting from an upward pull of a chain 112 separates the heads 118, 119 to bring about the well-known operation of the expandible pulleys inside the gear box. Springs 121 return the wedges to their lowest positions when the follower levers 109, 110 reach the sudden drop 108 in the cam 105. It is to be noted that while one of the levers, 109, 110 is operating its wedge 114, the other lever is riding on the semicircular portion 106 of the cam and its wedge remains stationary.

The drive to the traverse-box shaft 28 is taken from the clutch shaft 65 by two chain sprockets 122 driving two sprockets 123, 124, of slightly different size (Fig. 18). The sprocket 123 is rotatable on a member 125 secured to the shaft 28. The sprocket 124 is rotatable on the shaft 28 and carries a cam 126 lying within the mem-

ber 125 (Fig. 18). A cam follower 127 is carried by a pair of levers 128 connected at their end 129 to the sprocket 123 and at their end 130 to the member 125.

5 The member 125 is dragged round by the levers 128 as the sprocket 123 is driven, but, because the cam 126 is driven by the sprocket 124 at a slightly different speed from that of the sprocket 123, the cam operates the levers 128 to increase and decrease by a small amount the drag on the member 125. The shaft 29, to which the member 125 is secured, is thus given a slight irregularity of rotation, which, being transmitted by the shaft to the traverse mechanisms, serves to break up any tendency to "ribboning" in the building up of the threads on the cheeses.

10 The operation of the mechanism will now be briefly described:

15 With the clutch shaft 65 driven at a speed such that the spinning pumps 79 and the waste roller 75 effect the desired linear rate of production of artificial thread, the drive to the cam 105 is adjusted to bring about one half-revolution of the cam in the time that it will take to make the desired size of package. One set of spindles 3 occupies the position at the rear of the trunnion 1, i. e. substantially below the spinning cells. The gear-box 53 or 54 serving to drive this set of spindles is set in motion by operating the appropriate clutch 67 or 68 by one of the levers 71. At this time, the cam follower 109 or 110 for this gear-box has just left the semi-circular half 106 of the cam 105 for the half 107 having the steady lift, and the box is therefore serving to drive the spindles 3 at their highest angular speed, so that the empty supports 10 are running at the same peripheral speed as the waste roller 75.

20 The artificial threads 9 are being wound on the waste roller 75, and each thread is broken from the waste roller and transferred to its winding spindle 3 and threaded in its guide 12. Winding then continues on the supports 10 on the spindles 3, the peripheral speed of the package being maintained constant by steady diminution in the angular speed of the spindles as the lift of the cam 105 modifies the output speed of the gear box. (It should be noted that the profile of the lift 107 must be such as to compensate for the usual slight departure from uniform change of rate of operation of an infinitely variable gear. This means that the lift is not quite a true spiral, but is slightly modified—by an amount that cannot be shown on the scale of the present drawings—to give the necessary correction.)

25 During winding, the traverse frame 35 swings about its pivot 36 as the guide 12 is pushed away from the axis of the spindle 3 by the growing body of yarn. When the cheese-like package reaches the desired diameter—which may be determined on a time basis or by counting some number of revolutions of the waste roller shaft 74—the plunger 45 is released and the hand-wheel 43 is turned to rock the trunnion 1 about its axis until the plunger is re-engaged. This brings the loaded spindle 3 from the position shown in Fig. 8, through the position shown in Fig. 10, to the position shown in Fig. 11.

30 The guide 12 continues to traverse but is brought clear of the package at the beginning of the trunnion movement, by the following means:

35 At the left-hand end of the trunnion and co-axial with it is a sprocket 131 driving a further

sprocket 130' of half the size. The sprocket 130' is carried by a drum-cam 132, which therefore makes a full revolution during the half-revolution of the trunnion. During the period in which the cam 132 is stationary, a cam follower pin 133 projecting from the end of the traverse control rod 40 moves from position I to position II cross-wise of the cam (Fig. 16). When the cam begins to turn, the nose 134 pushes the pin 133 to position III and thus pulls the rod 40 to the left (Fig. 6). The engagement of the collars 136 on the rod 40 with the lugs 39 withdraws all the guides 12 away from the surfaces of their packages. By the time the cam 132 has brought the pin 133 to the position IV in the cam groove 135, the package has swung below the level of the guide 12 and the guide can be returned to its innermost position nearer the spindle 3 by the pin 133 moving to position V. The remainder of the cam groove is purely circumferential, so that the pin 133 returns to position I without affecting the position of the guide 12 in relation to the spindle 3.

During the early part of the swinging movement of the loaded spindle, the thread 9 is caused by the return of the guide 12 to its innermost position to engage the fixed guide 13 and is thereby prevented from falling over the innermost end of the package, being assisted in this respect by the offset position of the spindle. When the empty spindle reaches winding position (Fig. 11), the thread still being wound on the loaded package is engaged by the notches 22, which secure the thread to the spindle and break the length extending between the two spindles.

Just before the trunnion is rotated, the clutch handle 71 for the drive to the empty spindles is operated to set the spindles in motion, the corresponding gear-box 53 (or 54) being at this time set by the cam 105 to drive the spindles 3 at the maximum angular speed so as to give them a peripheral winding speed equal to that of the nearly loaded spindles. Thus, at the time the empty spindles reach winding position they are moving at the correct speed for receiving the threads 9 without snatch.

After the trunnion has been rotated, the other clutch lever is operated to stop the loaded spindles, the packages then being removed and replaced by empty supports.

A resetting handle 137 is carried by the shaft 98 to enable the cam 105 to be turned to the exact beginning of its cycle independently of its drive through the gear-box 104. This enables the correct winding speed to be immediately obtained at the spindles whenever a previous winding operation has been interrupted for any cause.

Having described our invention, what we desire to secure by Letters Patent is:

1. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, guides fixed to said casing, each near one of said spindles and spaced therefrom by an amount slightly exceeding the full radius of the cheese, and means for rotating said casing about its axis to remove one spindle from said traverse guide and to bring the other spindle alongside said traverse guide,

the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

2. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, guides fixed to said casing, each near one of said spindles and spaced therefrom by an amount slightly exceeding the full radius of the cheese, means for rotating said casing about its axis to remove one spindle from said traverse guide and to bring the other spindle alongside said traverse guide, and means adapted to withdraw said traverse guide from the surface of said cheese and to return it towards the axis of the spindle, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

3. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, guides fixed to said casing, each near one of said spindles and spaced therefrom, by an amount slightly exceeding the full radius of the cheese, means for rotating said casing about its axis to remove one spindle from said traverse guide and to bring the other spindle alongside said traverse guide, and means controlled by the rotation of said casing to withdraw said traverse guide from the surface of the cheese at the beginning of said rotation and to return said traverse guide towards the axis of the spindle at the end of said rotation, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

4. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, guides fixed to

said casing, each near one of said spindles and spaced therefrom by an amount slightly exceeding the full radius of the cheese, means for rotating said casing about its axis to remove one spindle from said traverse guide and to bring the other spindle alongside said traverse guide, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

5. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, guides fixed to said casing, each near one of said spindles and spaced therefrom by an amount slightly exceeding the full radius of the cheese, means for rotating said casing about its axis to remove one spindle from said traverse guide and to bring the other spindle alongside said traverse guide, means controlled by the rotation of said casing to withdraw said traverse guide from the surface of the cheese at the beginning of said rotation and to return said traverse guide towards the axis of the spindle at the end of said rotation, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

6. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, guides fixed to said casing, each near one of said spindles and spaced therefrom by an

amount slightly exceeding the full radius of the cheese, and means for rotating said casing about its axis to remove one spindle from said traverse guide and to bring the other spindle alongside said traverse guide, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

7. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, guides fixed to said casing, each near one of said spindles and spaced therefrom by an amount slightly exceeding the full radius of the cheese, means for rotating said casing about its axis to remove one spindle from said traverse guide and to bring the other spindle alongside said traverse guide, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

8. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, cam means for reducing the output speed of said gear box as the diameter of the cheese increases so as to maintain constant the peripheral speed of the cheese, guides fixed to said casing, each near one of said spindles and spaced therefrom by an amount slightly exceeding the full radius of the cheese, and means for rotating said casing about its axis to remove one spindle from said traverse guide and to bring the other spindle alongside said traverse guide, the axes of said spindles lying on opposite sides of the trunnion axis so that the field of traverse of the thread being wound remains within the length of the cheese until the rotation of said casing

causes said thread to be engaged by one of said fixed guides so that said thread may continue to be guided by said fixed guide to the surface of said cheese during the remainder of the rotation of said casing.

9. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, guides fixed to said casing, each near one of said spindles and spaced therefrom by an amount slightly exceeding the full radius of the cheese, and means for rotating said casing about its axis to remove one spindle from said traverse guide and to bring the other spindle alongside said traverse guide, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

10. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, cam means for reducing the output speed of said gear box as the diameter of the cheese increases so as to maintain constant the peripheral speed of the cheese, guides fixed to said casing, each near one of said spindles and spaced therefrom by an amount slightly exceeding the full radius of the cheese, means for rotating said casing about its axis to remove one spindle from said traverse guide, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

11. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, guides fixed to said casing, each near one of said spindles and spaced therefrom by an amount slightly exceeding the full radius of the cheese, means for rotating said casing about its axis to remove one spindle from said traverse guide and to bring the other spindle alongside said traverse guide, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

12. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, ratchet gearing for driving said cam, a re-setting handle for rotating said cam independently of the drive, guides fixed to said casing, each near one of said spindles and spaced therefrom by an amount slightly exceeding the full radius of the cheese, and means for rotating said casing about its axis to remove one spindle from said traverse guide and to bring the other spindle alongside said traverse guide, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

13. Cheese-winding apparatus comprising a

trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, ratchet gearing for driving said cam, a re-setting handle for rotating said cam independently of the drive, guides fixed to said casing, each near one of said spindles and spaced therefrom by an amount slightly exceeding the full radius of the cheese, means for rotating said casing about its axis to remove one spindle from said traverse guide, a notched member on each spindle, and guides on said casing for bringing a thread being wound on one spindle into contact with said notched member on the other spindle as the rotation of the casing brings the latter spindle alongside the traverse guide, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

14. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, cam means for reducing the output speed of said gear box as the diameter of the cheese increases so as to maintain constant the peripheral speed of the cheese, guides fixed to said casing, each near one of said spindles and spaced therefrom by an amount slightly exceeding the full radius of the cheese, means for rotating said casing about its axis to remove one spindle from said traverse guide, a notched member on each spindle, guides on said casing for bringing a thread being wound on one spindle into contact with said notched member on the other spindle as the rotation of the casing brings the latter spindle alongside the traverse guide, and means controlled by the rotation of said casing to withdraw said traverse guide from the surface of the cheese at the beginning of said rotation and to return said traverse guide towards the axis of the spindle at the end of said rotation, said notches being adapted, on contact with said thread, to apply a breaking tension to the length of thread between said spindles, the axes of said spindles lying on opposite sides of the trun-

nion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

15. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, guides fixed to said casing, each near one of said spindles and spaced therefrom by an amount slightly exceeding the full radius of the cheese, means for rotating said casing about its axis to remove one spindle from said traverse guide and to bring the other spindle alongside said traverse guide, a notched member on each spindle, guides on said casing for bringing a thread being wound on one spindle into contact with said notched member on the other spindle as the rotation of the casing brings the latter spindle alongside the traverse guide, and means controlled by the rotation of said casing to withdraw said traverse guide from the surface of the cheese at the beginning of said rotation and to return said traverse guide towards the axis of the spindle at the end of said rotation, said notches being adapted, on contact with said thread, to apply a breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.

16. Cheese-winding apparatus comprising a trunnion casing having at least one trunnion extending from an end thereof, a pair of winding spindles protruding from opposite sides of said casing, a traverse guide movable alongside one of said spindles to determine the length of a cheese to be wound on said spindle, said traverse guide being also movable away from said spindle as said cheese increases in size, two infinitely variable gear boxes for driving respectively said winding spindles, clutch means for rendering the drive effective through the gear box driving said spindle, a single cam controlling the speed of the operative gear box to reduce the output speed of said gear box as the diameter of the cheese increases so as to maintain constant the peripheral speed of the cheese, ratchet gearing for driving said cam, a re-setting handle for rotating said cam independently of the drive, guides fixed to said casing, each near one of said spindles and spaced therefrom by an amount slightly exceeding the full radius of the cheese, means for rotating said casing about its axis to

remove one spindle from said traverse guide, a notched member on each spindle, guides on said casing for bringing a thread being wound on one spindle into contact with said notched member on the other spindle as the rotation of the casing brings the latter spindle alongside the traverse guide, and means controlled by the rotation of said casing to withdraw said traverse guide from the surface of the cheese at the beginning of said rotation and to return said traverse guide towards the axis of the spindle at the end of said rotation, said notches being adapted, on contact with said thread, to apply a

breaking tension to the length of thread between said spindles, the axes of said spindles lying on opposite sides of the trunnion axis so that the field of traverse of the thread being wound remains within the length of the cheese until the rotation of said casing causes said thread to be engaged by one of said fixed guides so that said thread may continue to be guided by said fixed guide to the surface of said cheese during the remainder of the rotation of said casing.
